Primary Examiner — Stella Reid*Assistant Examiner* — Elizabeth J Oswecki(74) *Attorney, Agent, or Firm* — Michele V. Frank; Patton Boggs LLP(57) **CLAIM**

The ornamental design for a foldable artificial tree, as shown and described.

DESCRIPTION

FIG. 1 is a front view of a foldable artificial tree showing our new design, the back view being identical thereto.

FIG. 2 is a side view thereof, the opposite side view being identical thereto.

FIG. 3 is a bottom view thereof; and,

FIG. 4 is a top view thereof.

The dashed lines showing optional decorative elements in FIGS. 1-4 are for illustrative purposes only and form no part of the claimed design.
